UNITED STATES PATENT OFFICE.

JOHN H. ACKROYD, OF NEW YORK, N. Y.

CLOTH-BOARD AND SAMPLE-HOLDER.

No. 839,694.

Specification of Letters Patent.

Patented Dec. 25, 1906.

Application filed January 23, 1904. Serial No. 190,289.

To all whom it may concern:

Be it known that I, JOHN H. ACKROYD, a citizen of the United States, and a resident of the borough of Manhattan, in the city, county, and State of New York, have invented certain new and useful Improvements in Cloth-Boards and Sample-Holders, of which the following description and claims constitute the specification, which is illustrated by the accompanying sheet of drawings.

This invention comprises a new means for supplying a bolt of cloth with an apparatus for receiving and retaining in the interior of the bolt of cloth a separate strip of the same cloth and for permitting one end of that strip to be withdrawn from within the bolt of cloth just far enough to bring into view a sufficient area of the strip to be cut off and given away as a sample and for permitting this operation of withdrawal and cutting off to be repeated until the entire strip of cloth has been thus disposed of.

Figure 1 of the drawings is a perspective view of a cloth-board having a central longitudinal rectangular aperture extending therethrough. Fig. 2 is a cross-section on the line 2 2 of Fig. 1. Fig. 3 is a view of an open sample-holder, showing a sample strip of cloth properly placed therein. Fig. 4 is a central longitudinal section of the cloth-board of Figs. 1 and 2 with the sample-holder of Fig. 3 in place in the cloth-board. Fig. 5 is a perspective view of the cloth-board of Figs. 1 and 2 with the sample-holder of Fig. 3 and its sample-strip withdrawn from the cloth-board far enough to permit a sample to be severed from the outer end of the sample-strip. Fig. 6 is a perspective view of a modified sample-holder with a sample-strip 40 therein. Fig. 7 is a plan view of the sample-holder of Fig. 6 with both of its flaps open and without any sample-strip thereon.

The cloth-board is composed of two longitudinal strips A A and two longitudinal surface pieces B B, the inner edges of the two longitudinal strips being parallel to each other and having the longitudinal rectangular aperture C between them, and therefore extending through the body of the cloth-board lengthwise. The cloth-board may be made of pasteboard or stiff paper-board of sufficient thickness to give the necessary strength, or it may be made of wood or other suitable material, and the four parts which compose the cloth-board may be fastened to-

gether by glue, nails, or rivets, and preferably by both glue and nails. The aperture C may be about one-thirtieth the width of the cloth-board, or about two and one-half inches wide, and it may be from one-eighth to three-sixteenths of an inch in height or depth, and it may extend entirely through the cloth-board lengthwise.

The sample-holder D of Figs. 3, 4, and 5 consists of a piece of flexible cardboard or other suitable material having the body L and the side flap M and the end flap O, and which flap M is joined to the body L by the hinge-like joint E, and which flap O results from the slit H, and which body is provided with two lateral slots F F, having the integral lateral bar G between them, and which flap O has the tab J protruding from the cloth-board when the sample-holder is in place in the cloth-board to serve as a means of withdrawal of the sample-holder, with its sample-strip, partly out of the cloth-board, as shown in Fig. 5.

The sample-holder of Figs. 6 and 7 differs from the sample-holder of Figs. 3, 4, and 5 only in having an additional and shorter inner flap N, which is turned over upon its longitudinal hinge-like joint and is folded down upon the sample-strip K before the flap M of the sample-holder, and thus between the flap M and the sample-strip K.

The sample-strip K is a strip of equal width throughout, made by cutting a strip from the outer end of the cloth wound or folded around the cloth-board and entirely across that cloth in the direction of its width. The sample-strip K is attached to the sample-holder by passing one of its ends downward through one of the slots F and then upward through the other slot F, and then drawing the sample-strip through both slots about half-way of its length, and then laying those portions of the sample-strip which extend both ways from the bar G down upon the body L of the sample-holder. Thereupon the single flap of the sample-holder or the two flaps of the sample-holder, as the case may be, are folded down upon the sample-strip, and the sample-holder thus provided with the sample-strip is thrust into the aperture C in the cloth-board with only the tab J projecting therefrom, as shown in Fig. 4.

The folds of the holder have a tendency to spring apart and exert a binding pressure

against the walls of the aperture C on account of the flexible material of which the sample-holder is made, such binding pressure preventing the sample-holder from falling out of the aperture C and the walls of the aperture C operating to hold the sample-holder in a closed position.

The end portions of the sample-holder are bent apart in an open position, as shown, in order to expose a portion of the sample-strip contained therein, while the remaining portion of the sample-holder is held in a closed position in the aperture C. When the sample-holder is placed entirely within the aperture C, the walls thereof operate to bind the said end portions of the sample-holder together again and hold them in a closed position.

The mode of operation of this invention is as follows: When a salesman is about to give away a sample of the goods wound around the cloth-board, he clasps the tab J between his thumb and forefinger and withdraws the sample-holder from the cloth-board, about as far as is shown in Fig. 5, and then he turns the flap O upward, as shown in that figure, and thus exposes to view just enough of one end of the sample-strip to furnish a sufficient and economical sample of the cloth on the cloth-board, when he cuts off the exposed portion of the sample-strip and presents it to the prospective customer. Thereupon he draws the new end of the sample-strip out to the end of the sample-holder, and then he pushes the sample-holder back into the aperture C of the cloth-board. Afterward he repeats the operation whenever he is about to give away a sample of the cloth.

Where the cloth wound around my cloth-board is of double width, a sample-strip cut from its loose end will be twice as long as the cloth-board and must therefore be folded once crosswise upon itself when placed in my sample-holder, as shown in Fig. 3 of the drawings. In this case the bar G is particularly useful in preventing the wrinkling of the sample-strip when it is being placed or after it has been placed in the sample-holder, and also in preventing any misplacement of the sample-strip in case the sample-holder is entirely withdrawn from the cloth-board by some salesman in a particular case instead of being only partly withdrawn, as shown in Fig. 5.

Where the cloth wound around my cloth-board is of single width, a sample-strip cut from its loose end will not be longer than the cloth-board. In this case if the sample-holder is as long as the cloth-board the sample-strip may be laid upon the body of the sample-holder without being folded over crosswise upon itself.

The utility of the flap O resides in a number of particulars, including the fact that if that flap were absent and the sample-holder

were to be withdrawn from the cloth-board by pulling upon the outer end of its body L the friction of the upper side of the aperture C would tend to hold back and wrinkle the forward end of the sample-strip K and including the fact that if the material of the flap O were present, but without any slit H between that material and the body L of the sample-holder, there would be no room or opportunity to cut off a sample from the forward end of the sample-strip inside of the forward end of the body of the sample-holder.

I claim as my invention—

1. A sample-holder having a long and narrow body L, upon which a long and narrow sample-strip K may be placed, and having a long and narrow flap M, attached to one side of the body L, by a long hinge-like joint E; and having a short flap O, extending from the flap M, and separated from the body L, by the slit H; all substantially as described.

2. A sample-holder having a long and narrow body L, upon which a long and narrow sample-strip K may be placed, and having a long and narrow flap M, attached to one side of the body L, by a long hinge-like joint E; and having also a bar G, for the attachment of the sample-strip to the sample-holder; all substantially as described.

3. A sample-holder having a long and narrow body L, upon which a long and narrow sample-strip K may be placed, and having a long and narrow flap M, attached to one side of the body L, by a long hinge-like joint E; and having a short flap O, extending from the flap M, and separated from the body L, by the slit H; and having also a bar G for the attachment of the sample-strip to the sample-holder; all substantially as described.

4. A sample-holder comprising a long and narrow strip of pasteboard or other flexible material folded over upon itself to form an inclosure having one end open, the folds of which are adapted to spring apart in an open position, in combination with a cloth-board having an aperture in its body receiving said sample-holder and holding the folds thereof in a closed position, whereby a sample strip of cloth contained in said inclosure is adapted to be withdrawn therefrom through the open end thereof while the sample-holder is held in a closed position in the aperture.

5. A board for winding thereon textile cloth or fabrics having an aperture in its body, in combination with a sample-holder held in a closed position by insertion in said aperture and having a portion of its length adapted to be withdrawn from said aperture and opened to expose a portion of a sample strip of cloth contained therein while the remaining portion of its length is held in a closed position in said aperture.

6. A board for winding thereon textile cloth or fabrics having an aperture in its body, in combination with a sample-holder

having one end open and held in a closed position by insertion in said aperture whereby a sample strip of cloth contained in said sample-holder is adapted to be withdrawn therefrom through the open end thereof while the sample-holder is held in a closed position in the aperture.

Signed at New York, in the county of New York and State of New York, this 22d day of January, A. D. 1904.

JOHN H. ACKROYD.
